UNITED STATES PATENT OFFICE.

ELIZA ANN BLAKER, OF INDIANAPOLIS, INDIANA.

DESIGN FOR A SPOON, &c.

SPECIFICATION forming part of Design No. 22,375, dated May 2, 1893.

Application filed January 7, 1893. Serial No. 457,691. Term of patent 7 years.

To all whom it may concern:

Be it known that I, ELIZA ANN BLAKER, a citizen of the United States, residing at Indianapolis, in the county of Marion and State 5 of Indiana, have invented certain new and useful Improvements in a Design for the Handles of Spoons, &c.; and I do hereby declare the following to be a full, clear, and exact description of the design, such as will enable others skilled in the art to which it appertains to make and use the same.

This invention relates to a new and original design for the handles of spoons, knives or forks, reference being had to the accompanying drawing which forms a part of this application.

The drawing shows a side elevation of a spoon in which the handle is fashioned in accordance with my design the leading features 10 of which consists in a handle surmounted by a bust of Friedrich W. A. Froebel the German educator prominently identified with the origin and introduction of the "kindergarten

"system of early education for children. The design also consists in a representation 25 of childhood and also in the display of the lily and the daisy which were Froebel's favorite flowers.

As illustrated in the accompanying drawing, the bust of Froebel terminates the outer 30 end of the handle and childhood is represented by the figures of a boy and a girl dancing about the bust. A lily is shown immediately under the representation of childhood and the inner end of the handle terminates in 35 a grouping of daisies.

I claim—

The design for the handles of spoons, &c., substantially as shown and described.

In testimony whereof I affix my signature in 40 presence of two witnesses.

ELIZA ANN BLAKER.
